CLAIM

The ornamental design for a low profile electrical terminal, as shown and described.

DESCRIPTION

FIG. 1 is a perspective view of a low profile electrical terminal showing my new design;

FIG. 2 is a side elevation view thereof;

FIG. 3 is an opposite side elevation view thereof;

FIG. 4 is an end elevation view thereof;

FIG. 5 is an opposite end elevation view thereof;

FIG. 6 is a top plan view thereof; and,

FIG. 7 is a bottom plan view thereof.
